UNITED STATES PATENT OFFICE.

LE ROY K. VAN HORN, OF YOUNGSTOWN, OHIO.

MOLD FOR MAKING CONCRETE STRUCTURES.

1,120,569.

Specification of Letters Patent.

Patented Dec. 8, 1914.

Application filed August 29, 1912. Serial No. 717,740.

To all whom it may concern:

Be it known that I, LE ROY K. VAN HORN, a citizen of the United States, residing at Youngstown, in the county of Mahoning and State of Ohio, have invented certain new and useful Improvements in Molds for Making Concrete Structures, of which the following is a specification.

My invention relates to molds for cement or concrete walls, and particularly to detachable, adjustable molds.

The object of this invention is to provide means of this character for forming cement walls, beams, columns, piers, sea walls, etc., of uniform or varying thickness, or any regular geometric shape, and having plane, offset, or beaded surfaces.

Another object is to provide a structure of this kind for forming ceilings, girders and floors.

An important object is to provide a structure of this character which is composed of plane sections, adjustable angle and corner sections, and curved sections coöperating with fillers which are all easily detachable from the molded wall.

Another important object is to provide sections of varying lengths coöperating with adjustable corner sections, in order that the molds may be adjustable to a very small degree for forming walls of any length desired.

A further object is to provide efficient and simple means for spacing and securing the two walls of the mold.

Still another object is to provide means for quickly and easily attaching together the different plates which form the walls of the mold.

With these and other objects in view my invention consists in the novel arrangement and combination of parts as more fully set forth in the following description and claims.

Referring to the drawings forming a part of this specification and in which like numerals are used to designate corresponding parts throughout the several views: Figure 1 is a perspective view of my mold for forming a plane, straight wall, Fig. 2 is a perspective view of an angle plate, Fig. 3 is a horizontal section of an angle mold, Fig. 4 is a perspective view of a filler used in constructing an angle, Fig. 5 is a perspective view of a box or corner filler used in constructing ceilings, Fig. 6 is an end view of

the mold as arranged for forming a wall of uniform thickness, Fig. 7 is an end view of the mold as arranged for forming a wall tapering toward the top, Fig. 7^a is a detail view of a tie-rod, Fig. 8 is a fragmentary perspective view of a modified form of plate, Fig. 9 is a perspective view of a plane and angular mold formed of this modified form of plate, and a section of wall molded thereby, Fig. 10 is a perspective view of various plates arranged to form a wall, a ceiling and girder in one operation, Figs. 11, 12 and 13 are perspective views of securing bars for holding the plates in ceiling construction, Fig. 14 is a perspective view of plates arranged to form a wall, cornice and pitched roof in one operation, Fig. 15 is a perspective view of plates arranged to form a girder, Fig. 16 is a horizontal section through plane and curved plates arranged to form a column projecting from a wall, Fig. 17 is a perspective view of two of the curved plates provided with offset portions for receiving secondary molds for ornamentation, Fig. 18 is a detail section through the union of two such plates, Fig. 19 is a perspective view of a fragment of a wall mold provided with reinforcing supports, Fig. 20 is a perspective view of a clamp for holding the hooks and staples of contiguous plates from displacement, and Fig. 21 is a sectional view of a wall showing means for removing the tubes.

Referring more particularly to the drawings, the numeral 1 designates a flat plate preferably of iron or steel, and of any desired size, except that it should be a multiple of any desired unit. These plates are provided along one side and one edge with angular hooks 2, and along the other side and edge with rectangular sockets 3. The hooks and sockets on adjacent plates are to co operate with each other as shown. If desired, these hooks and sockets, after being placed in engagement, may be locked together by means of the locking member 4, as shown in Fig. 21. The plates 1 are also provided with openings 5, to receive tie-rods 6 which pass through the tubular spacing elements 7 disposed between the outer and inner plates of the mold, and abutting against the inner opposing faces of the same. These tie-rods comprise a head 8, formed tubular for the reception of a bar or the like for removing the rod from the wall when molded, and an extended body portion 9 provided

with openings 10 throughout its length for the reception of locking pins or wedges 11.

It will be readily seen that the thickness of a wall may be changed or varied by using 5 spacing tubes of different lengths, and inserting the wedges 11 in the required hole 10, for clamping the walls in their spaced relation, as shown in Fig. 7.

Adapted to coöperate with the plates 1 are 10 adjusting angle or corner sections 12. These corner sections illustrated in Figs. 2 and 3 form an important part of the invention, as by their use, the length of a wall may be varied to as small a degree as one inch. 15 The corner or angle sections are applied to the outside and inside of the outer and inner walls of the straight mold as shown, and are merely plates preferably bent to any desired fixed angle. The corner sections 20 12 have openings 13 in their two angular sides for the reception of the hooks 2 on the edges of the plates 1 and are also provided with openings 14 for the reception of the tie-rods 6, and a series of openings 15 25 for a purpose to be described. In order that these corner sections will mold a wall having a smooth surface, I provide fillers 16 contacting with the inside and outside of the outer and inner angle plates, respectively, as shown clearly in Fig. 3. These fillers are composed of a series of filler plates, as shown in detail in Fig. 4. The filler comprises an angular plate 17, and a series of plates 18 and 19. The plates 18 30 and 19 may be of any desired width, but it is preferable to form all plates the multiple of a certain unit for purposes of adjustment.

The purpose in having the fillers in sections is to enable a corner to be properly filled so that the walls of the mold will be flush, regardless of whether a short angular filler plate, or a more extended filler is required.

45 In order to secure the filler plates to the angle or corner plates, I provide them with a series of openings 20 adapted to register with the openings 15 in the corner or angle plates, and adapted to receive clamping 50 bolts 21. It will be noted that one of the openings 20 is disposed at the edge of each filler plate, so that the wide flat heads 22 of the bolts will overlap the union of each contiguous plate, and thus hold them in place. 55 The filler plates are further provided with apertures 23 for receiving the tie-rods for holding the forms together.

In Figs. 8 and 9 I have shown the same general construction of mold, except that 60 the plates, angles and fillers are provided with offset portions 24. These plates are adapted to form a stepped wall. By securing molding 25 of any desired design within these offset portions 24, it is possible to 65 form a wall having ornamental beading or

molding upon its surface, as shown at 26. It will be understood that the tie openings will have to extend through the molding.

In Fig. 10 I have shown an arrangement of plates, angles and fillers for forming 70 walls, a ceiling, and a girder in one operation. 27 indicates a wall mold, 28 the ceiling mold, and 29 a girder mold. The plates 1, angles 12 and fillers 16 are arranged vertically in the wall mold, and horizontally in 75 the ceiling and girder mold 28, as shown. In order to form the inner corners of the ceiling, I provide corner boxes 30 illustrated in detail in Fig. 5, which are bolted in place by means of securing braces 31, 32 80 and 33. These securing braces are provided with bolt receiving apertures 34, and tie receiving openings 35. Of course, in this instance it will be necessary to support this mold structure. For this purpose I employ 85 arrangement of planks 36, and upright posts or supports 37.

In Figs. 14 and 15 I have shown my molds adapted for girder construction, to be used in connection with a wall or ceiling, 90 or separately. In this instance it will be noticed that scaffolding comprising horizontal planks 38 and vertical posts 39 is required to maintain the mold in its elevated position. These girder molds comprise 95 plane plates or plates either angular or plane provided with offsets 40 secured in end to end relation, spaced apart by the tubes 7 and clamped by means of the tie-rods 6. Within the offsets 40 moldings 41 100 of any desired shape may be bolted as at 42 for ornamental effect. In order to support the angular plates a brace 43 may be provided having therein an aperture 44 for the reception of a tie-rod 6.

105 In Figs. 16 to 18, I have illustrated my mold structure adapted to mold a column either connected with or separate from a wall. This structure comprises curved plates 45 having straight portions 46 extending therefrom for connection with the plane plates 1. The portions 46 are of the same construction as each leg of the angle plates, and are provided with openings 47 for the reception of bolts 48, having flattened wide heads 49, by means of which the filler plates 16 are secured. The curved plates 45 are also provided with hooks and staples of the same as on the plane plates. When it is desired to bring two of the 110 curved plates closely together, I provide a bar 50 between them, which may be of any desired thickness. A bolt passes through the portion 46 of the plates and the bar 50, thus holding them securely together. In 115 order to prevent accidental turning of this bolt, a rivet or pin 52 is inserted within an opening through the bar 50 and the bolt 51 as shown. These curved plates 45 may be formed with offsets 53 within which mold- 120 125 130

ing 54 may be secured by means of bolts 55, for forming ornamental bases for columns.

In very heavy work it is sometimes desirable to strengthen the walls of the mold. 5 With this end in view, I provide a reinforcing means illustrated in Fig. 19. This reinforcement consists of a series of crosses or spiders 56 disposed upon each of the tie-rods 6, with the extremities of their arms 10 abutting against each other as shown at 57. Each cross or spider is provided with an opening 58 at the junction of its arms for receiving the tie-rod.

After the cement has been poured into the 15 molds, and "set" or hardened, the wedges are removed from the tie-rods, the tie-rods are withdrawn, and the plates are removed. It will be noted that the spacing tubes 7 will then remain in the wall. In order to 20 remove these tubes I provide a device illustrated in Fig. 21, comprising a cylindrical portion 59 of the same diameter of the tube, and having a reduced end 60 which is adapted to be inserted within the tube. It will be 25 readily seen that the blow upon this device will cause the shoulder 61 to force the tube out of the wall.

Having thus described my invention what I claim is:

30 1. In a cement wall mold structure, straight wall sections coöperating with adjustable reversible corner sections, said straight sections and corner sections being adapted to be adjustably secured to each 35 other by means of securing elements upon the wall sections extending through openings in the plates of said corner sections, and filler plates adapted to be disposed within the corner sections and abut against 40 the edges of the plates of the wall sections to make a smooth and flush molding surface, said filler plates being provided with apertures for the passage of securing means engaging said corner sections.

45 2. In a structure of the character described, wall sections adjustably and detachably connected with angular sections, and filler plates secured to said angular sections, and adapted to abut against the ends 50 of said wall sections to produce a flush joint, said fillers being secured to said angular sections and comprising a plurality of plates of the same thickness as said wall sections.

55 3. A cement wall mold structure comprising spaced plane wall sections provided with apertures, angular corner sections for coöperation with said plane sections and provided with elongated openings, and tie bars passing through said elongated openings and said apertures for holding said sections in spaced relation.

4. A cement wall mold structure comprising spaced plane wall sections provided with apertures, outer and inner angular corner sections for coöperation with said plane

sections and provided with elongated openings and a plurality of apertures, filler plates disposed against the inner and outer faces of said outer and inner angular sections, respectively, and provided with apertures aligned with said apertures in said corner sections, bolts passing through said second and third named apertures, said filler plates being further provided with other apertures in alignment with said first and last named apertures and said elongated openings, and tie bars passing through said first and last named apertures and said elongated openings for holding said sections in spaced relation.

5. In a cement wall mold structure, plates provided with sockets adjacent two of their edges and rigid hooks adjacent their other two edges, said hooks and sockets being adapted to interlock with the sockets and hooks on contiguous plates arranged in tiers and in end to end relation, and removable clips adapted to engage said hooks and sockets in their locked position for preventing their displacement, said clips being provided with inclined slots engaging said hooks and said sockets for forcing and holding them together.

6. In a cement wall mold structure, plates provided with sockets adjacent two of their edges and rigid hooks adjacent their other two edges, said hooks and sockets being adapted to interlock with the sockets and hooks on contiguous plates arranged in tiers and in end to end relation, and removable 95 clips adapted to engage said hooks and sockets in their locked position for preventing their displacement, said clips comprising blocks provided with a pair of slots converging toward one end, said slots forming 100 three wedging tines upon said blocks, one of said tines engaging a socket, one engaging a hook, and the other being disposed between the horizontal portion of the hook and the socket.

7. A cement wall mold structure comprising spaced plane wall sections, outer and inner angular corner sections detachably connected therewith, and angular filler plates disposed against the inner and outer 115 faces of the outer and inner corner sections, respectively, said filler plates being of the same thickness as said plane sections and abutting against the edges thereof and secured to the corner sections.

8. A cement wall mold structure comprising spaced plane wall sections, outer and inner angular corner sections detachably connected therewith, said angular sections being provided with apertures, filler plates 125 disposed against the inner and outer faces of the outer and inner corner sections, respectively, said filler plates being provided with apertures and formed of the same thickness as said plane sections and abutting 130

against the edges thereof, and bolts passing through said first and last named apertures for securing said filler plates to said corner plates.

- 5 9. A cement wall mold structure comprising spaced plane wall sections provided with apertures, outer and inner angular corner sections detachably connected with said plane sections and provided with elongated 55 apertures adapted to aline with said first named apertures, means extending through said first and second named apertures for holding said sections in spaced relation, and 60 filler plates detachably connected with said corner sections disposed against the inner and outer faces of said outer and inner corner sections, respectively, and abutting against the ends of said plane sections.

10. A cement wall mold structure comprising spaced plane wall sections provided with apertures, outer and inner angular corner sections detachably connected with said plane sections and provided with elongated 65 apertures adapted to aline with said first named apertures, means extending through said first and second named apertures for holding said sections in spaced relation, and 70 filler plates detachably connected with said corner sections disposed against the inner and outer faces of said outer and inner corner sections, respectively, and abutting against the ends of said plane sections.

- 20 11. In a cement wall mold structure, spaced walls comprising a plurality of interlocked plates, tubular members for spacing said walls apart, locking members extending through said walls and said tubular 75 members, and reinforcing means mounted upon said locking members and contacting with the outer faces of the walls, said reinforcing means comprising spiders provided with a central aperture for the passage of

- 25 the locking members, and having the ends of their legs mitered and interfitting.
- 30 12. A cement wall mold structure comprising spaced plane wall sections provided

with apertures, outer and inner angular corner sections detachably connected with said 50 plane sections and provided with elongated apertures adapted to aline with said first named apertures, means extending through said first and second named apertures for holding said sections in spaced relation, and 55 filler plates detachably connected with said corner sections disposed against the inner and outer faces of said outer and inner corner sections, respectively, and abutting against the ends of said plane sections, said 60 filler plates comprising a rigid angular portion and a plurality of plane portions, said angular and plane portions of said filler plates being a multiple of a predetermined unit.

65 13. A cement wall mold structure comprising spaced plane wall sections provided with apertures, outer and inner angular sections provided with elongated openings adapted to aline with said apertures, tie bars 70 passing through said elongated openings and said apertures for holding said sections in spaced relation, and means contacting with the inner opposing faces of said angular sections for filling the spaces between the 75 ends of said wall sections and the angle of said angular sections for forming a flush mold.

14. A cement wall mold structure comprising spaced plane wall sections provided 80 with apertures, outer and inner angular sections provided with elongated openings adapted to register with said apertures, and tie bars extending through said elongated 85 openings and said apertures for holding said wall sections in their spaced relation and securing said angular sections longitudinally adjustably upon said plane wall sections.

In testimony whereof I hereto affix my 90 signature in the presence of two witnesses.
